(57) **CLAIM**

The ornamental design for a side cheek of an audio mixing board, as shown and described.

DESCRIPTION

FIG. 1 is a side elevational view of the right-hand side cheek of an audio mixing board showing a first embodiment of my new design;

FIG. 2 is a perspective view thereof;

FIG. 3 is a top plan view thereof;

FIG. 4 is a front elevational view thereof;

FIG. 5 is a rear elevational view thereof;

FIG. 6 is a side elevational view of a left-hand side cheek of an audio mixing board showing a second embodiment of my new design;

FIG. 7 is a perspective view thereof;

FIG. 8 is a top plan view thereof;

FIG. 9 is a front elevational view thereof; and,

FIG. 10 is a rear elevational view thereof.

The broken line showings form no part of the claimed design.
